UNITED STATES PATENT OFFICE.

ELMER H. SCHWARZ, OF GLEN ROCK, NEW JERSEY, ASSIGNOR TO THE DAYTON ENGINEERING LABORATORIES COMPANY, A CORPORATION OF OHIO.

IGNITION SYSTEM.

1,375,736.

Specification of Letters Patent. Patented Apr. 26, 1921.

Application filed November 22, 1917. Serial No. 203,314.

To all whom it may concern:

Be it known that I, ELMER H. SCHWARZ, citizen of the United States of America, residing at Glen Rock, county of Bergen, 5 State of New Jersey, have invented certain new and useful Improvements in Ignition Systems, of which the following is a specification.

This invention relates to improvements 10 in combined ignition and starting systems, for internal-combustion engines, both of the single-unit type where the electric motor for starting the engine also acts as a generator after the engine has started, and of the two-unit type where separate motor and generator units are employed.

In systems of this character where the ignition current is supplied by storage batteries in conjunction with a charging generator, it is considered advisable to protect 20 the ignition circuit against overload at low engine speed, particularly when the engine comes to rest with the contact points of the ignition breaker together. If the ignition switch is not opened under such conditions, 25 an abnormal current will flow from the storage battery through the primary circuit of the induction coil. This will rapidly exhaust the battery and endanger, if not 30 burn out, the primary coil. My invention provides improved means for properly safeguarding the ignition circuit and storage batteries.

I will now describe the means embodying 35 my invention illustrated in the accompanying drawings, and will thereafter point out the novel features in the claims.

Figure 1 is a wiring diagram showing the 40 circuit connections of a starting, lighting and ignition system of the two-unit type to which my invention has been applied;

Fig. 2 shows the invention similarly applied to a single-unit system; and

Fig. 3 shows a modification of the invention 45 which may be applied to either a single- or a two-unit system.

Referring to Fig. 1, the motor starting circuit is indicated by heavy lines while the generator and ignition circuits are indicated 50 by light lines. The motor circuit is as follows:

From the positive side of the battery 1 through the wires 2, 3 and 4, to the series field 5 and the armature 6 of the starting 55 motor, and through the starting switch 7

to the negative side of the battery 1. The closing of the starting switch 7 rotates the engine which is of the internal-combustion type and not self-starting. After the engine has started under its own power, the 60 starting switch is released and is opened by a spring as is usually the case. The generator is of the shunt type, either self-excited as shown or excited from the storage 65 battery, and consists of the armature 8 and the shunt field 9. As soon as the engine is started the generator begins to "pick up," that is, a voltage is established across the armature 8 which increases with the speed 70 of the engine, and which, when it reaches a predetermined value, causes the automatic switch 10 to close and to establish connections between the generator and the storage battery. The automatic switch 10 is magnetically operated and controlled by a shunt 75 coil 11 and a series coil 12, which act upon the iron core 13 which attracts the movable armature 14 to which the movable contact 10^a of the switch is attached. The shunt coil 11 is connected across the armature 8 80 and its current is therefore proportional to the voltage set up in said armature. The shunt coil 11 therefore controls the closure of the switch 10 at a predetermined value 85 of the generator voltage. When the switch 10 closes, the generator circuit is established as follows:

From the positive brush of the generator, through the wire 2 to the positive side of the storage battery 1, through said battery 90 to the negative side, through the wire 15, through the contacts 10^a and 10^b of automatic switch 10, the series coil 12 of said switch, and through the wire 16 to the negative side of the generator armature 8. The 95 generator is now charging the storage battery, since the automatic switch 10 is so adjusted that it will not close until the generator voltage exceeds that of the battery. The series coil 12 of the automatic switch 100 is so connected that the magnetism set up thereby is in the same direction as that of the shunt coil 11 when the generator is charging the storage battery. If, however, the speed of the generator is so reduced that 105 its voltage falls below that of the storage battery, the generator armature current is then reversed with a similar reversal of current through the series coil 12. The magnetism set up by this coil will then oppose 110

that of shunt coil 11, and the contacts 10^a and 10^b of the automatic switch 10 will then open and cut off the generator from the storage battery. The construction and operation of an automatic switch of this type have long been well known, and any of the forms of construction of said switch are applicable to my system.

It remains to trace out the ignition circuit, which is as follows: from the positive side of the generator, through the wires 3 and 17, through the primary coil of the induction coil 18, the ignition breaker 19, the ignition switch 20, the wires 21 and 22, the series coil 12 of the automatic switch 10, and the wire 16 to the negative side of the generator. It will therefore be seen that the ignition circuit is connected directly across the terminals of the armature 8 of the generator, and on the inside of the automatic switch 10, so that if the automatic switch is open the ignition current will be provided only by the generator, and the voltage of the ignition circuit will in that event be proportional to the speed of the generator. This, therefore, guarantees regulation of and protection to the ignition circuit at low speeds, since the voltage will be decreased in proportion to the decreased resistance or reluctance of the ignition circuit at low speeds. Also, since the battery is cut off from the ignition circuit at this time, there will be no danger of exhausting the batteries.

It may be desirable in starting the engine to supply the ignition current from the battery since at this time it is advantageous, particularly at the low speed at which the engine rotates, to have a strong current passing through the ignition circuit. To this end I may provide an extra contact 23, on the starting switch 7, which establishes a momentary short circuit across the contacts 10^a and 10^b of automatic switch 10, thus supplying the ignition circuit with current from the storage battery 1 at starting. With such an arrangement, it will be observed that the generator will also be connected across the storage battery, through the starting switch 50 7 and the auxiliary contact 23, and the generator, on account of its low speed, will tend to act as a motor and to receive current from the storage battery. Due to the high resistance of the armature 8 of the generator, this current will be small in amount and it will be used for a short period of time only, and the effect therefore on the storage battery will be almost negligible. Means are also provided for placing the short circuit around the contacts 10^a and 10^b of automatic switch 10, in case, for any reason, it is necessary to start the engine by the hand crank 24. This means consists of a pivoted movable switch member 25, which is engaged by 60 the hand crank member 24, when the crank

handle is pushed in to engage the clutch 24^a on the outer end of the crank shaft, as shown in Fig. 1. The movable contact 25 will then engage the stationary contact 26, which, as will be seen, places a short circuit 70 around the contacts of the automatic switch 10 through a ground connection, and thus the ignition circuit is supplied directly from the storage battery and the engine is started by hand. A spring 27 opens the contacts 75 25 and 26 when the crank handle 24 is released.

Fig. 2 is similar to Fig. 1, except that the novel ignition circuit connections are applied to a single-unit system where the starting 80 motor acts also as a generator to charge the storage battery after a predetermined speed has been reached and the automatic switch is closed. In this case, I have shown the dynamo-electric-machine provided with a 85 shunt-winding 9 and a series-winding 9^a, so connected that they act accumulatively when the dynamo-electric-machine is acting as a motor, and differentially when acting as a generator, as a means of current regulation 90 for varying speeds of the generator. Different forms of windings and of regulation might be used, however, and I do not wish to limit the invention in this respect. Where a single machine performs the functions of 95 both a generator and a motor, it will be observed that the starting switch 7 will, when closed, place a short circuit around the contacts 10^a and 10^b of the automatic switch 10. In this case, therefore, it is unnecessary 100 to provide the extra contact 23 on the starting switch as in Fig. 1. It should be understood that I prefer to provide the hand crank 24 with means for establishing a short circuit around the automatic switch 10 in Fig. 105 2, similarly to Fig. 1.

In Fig. 3 I have shown a modification of my invention, in which the ignition circuit is connected directly across the battery 1, and in which I rely chiefly on the alarm device 28 to protect the ignition circuit. The alarm device 28 is connected to automatic switch contact 10^a and between the ignition switch 20 and the ignition timer 19. Of course, in this case, the signaling device 28 115 is chiefly advantageous if the ignition breaker contacts of the breaker 19 happen to be closed when the engine stalls but it is of course an advantage to be reminded, in any event, that the ignition switch 20 should 120 be opened. The connection shown, however, has an added advantage in notifying the driver when the automatic switch opens and the generator is no longer charging the storage battery. The engine might be running 125 very slowly at this time and the condition of the battery might be such that it would be desirable to speed up the engine so as to close the automatic switch 10 and begin to charge the storage battery. 130

I may add to the ignition circuit, in Fig. 3, a resistance 33 made of iron wire or other wire having a high temperature coefficient. The resistance of such a wire increases considerably upon overload and therefore acts as a compensator to keep the ignition current within bounds until the driver opens the switch 20. The use of an iron-wire resistance in the ignition circuit constitutes no part of my invention, but is the subject matter of U. S. Patent 1,223,180 to Charles F. Kettering, dated April 17, 1917. The generator of Fig. 3 can either be the generating unit of a two-unit system such as illustrated in Fig. 1, or the dynamo-electric machine of a single-unit system such as is illustrated in Fig. 2. The connections would be the same in either case, being applied to the generator in the first place and to the dynamo-electric-machine in the second place.

While the forms of mechanisms herein shown and described constitute preferred forms of embodiments of the invention, it is to be understood that other forms might be adopted, all coming within the scope of the claims which follow.

What I claim is as follows:

1. In an electric charging system, the combination with a battery, a generator for charging said battery; circuit connections between the battery and generator, including an automatic switch for disconnecting the generator from the battery when the voltage of the generator is lower than the voltage of the battery; and a signaling device, operable upon the opening of said automatic switch, said device, when operable, being arranged in series between the battery and generator.

2. In an electric charging system, the combination with a battery, a generator for charging said battery; circuit connections between the battery and generator, including an automatic switch for disconnecting the generator from the battery when the voltage of the generator is lower than the voltage of the battery; and a signaling device which is connected across the contacts of said automatic switch, said device, when operable, being arranged in series between the battery and generator.

3. In an electric charging system, the combination with a battery, a generator for charging said battery; circuit connections between the battery and generator, including an automatic switch for disconnecting the generator from the battery when the

voltage of the generator is lower than the voltage of the battery; and a signaling device which is operable when the battery voltage exceeds the generator voltage by a predetermined amount, said device, when operable, being arranged in series between the battery and generator.

65

4. In an electric charging system, the combination with a battery, a generator for charging said battery and circuit connections between the battery and the generator; of an independent circuit including a signaling device operable upon a predetermined generator speed, said signal device, when operable, being arranged in series between the battery and generator.

70

5. In an electrical system, the combination with a battery and a generator for charging the same; ignition devices having electrical connections with the battery and generator; a manually operable switch to control the ignition circuit; and an electrical signaling device operable after the generator reaches a predetermined low speed, said device being operative only as long as the ignition switch remains closed.

75

6. In an electrical system, the combination with a battery; of a generator for charging the battery; ignition devices normally connected with the generator; manual means for connecting the ignition devices and battery for engine starting purposes; and automatic means for connecting the generator and battery for charging purposes upon attainment of a predetermined generator speed, said automatic means operable to disconnect the generator and battery while permitting the ignition devices to remain connected to the generator.

80

7. In an electrical system, the combination with a battery and a generator for charging the same; ignition devices having electrical connections with the battery; a switch for controlling the ignition circuit, automatic means for disconnecting the battery from the generator when the voltage of the generator is lower than the voltage of the battery; and a signaling device operable after the battery voltage exceeds the generator voltage, said device being operative only as long as the ignition switch remains closed.

10

In testimony whereof I affix my signature in presence of two witness.
